UNITED STATES PATENT OFFICE.

WILLIAM G. KENDALL, OF NEWARK, NEW JERSEY.

VANITY-BOX.

1,229,285.

Specification of Letters Patent. Patented June 12, 1917.

Application filed March 22, 1916. Serial No. 85,968.

To all whom it may concern:

Be it known that I, WILLIAM G. KENDALL, a citizen of the United States, residing at Newark, in the county of Essex and State 5 of New Jersey, have invented certain new and useful Improvements in Vanity-Boxes, of which the following is a specification.

My invention relates to new and useful improvements in vanity boxes, the primary 10 object of my invention being the provision of a combined rouge box and pad in which the powdered rouge may be compressed into suitable tablet form directly upon the bottom of the box and in which the box is so 15 shaped as to lock the tablet of rouge thus formed in place without the use of adhesives or other fastening means.

A still further object of my invention is to provide a novel form of hinged cover for 20 the box of such a character that the box and cover may be stamped out by suitable dies and assembled without the use of solder, riveting or other fastening means of like nature.

25 A further object of my invention is to so construct, either the box or the cover, as to adapt one or the other of them to hold a mirror.

Another object which I have in view is to 30 provide the rouge holding box which does away with the employment of the ordinary rouge holding pad which, as a rule, carries the rouge and is mounted in a box and which is, therefore, more compact and more readily 35 carried in a purse.

With these and other objects in view, my invention will be more fully described, illustrated in the accompanying drawings, and then specifically pointed out in the claims 40 which are attached to and form a part of this application.

In the drawings:

Figure 1 is a perspective view of my vanity box in open position, the puff being re- 45 moved from the box;

Fig. 2 is a vertical central sectional view, showing the construction of the box and its hinge, the puff being also removed in this view to more clearly show certain details;

50 Fig. 3 is a transverse sectional view on the line 3—3 of Fig. 2, looking in the direction of the arrows and showing the manner of anchoring a mirror against the inner face of the cover of the box;

55 Fig. 4 is an elevation, partially in vertical section, of a modified form of box structure

in which the mirror is mounted in the outer face of the bottom of the box;

Fig. 5 is a bottom plan view of the form of box shown in Fig. 4.

Corresponding and like parts are referred to in the following description and indicated in all the views of the drawings by the same reference characters.

My improved vanity box, as best shown 65 in Figs. 1 and 2 of the drawings, includes a cylindrical body portion 10 flaring outwardly at its lower end, as shown at 11, and closed by an integrally formed bottom 12. This box is closed by a cover including a top 70 proper 13 having a downwardly depending annular flange 14 adapted to engage about the upper edge of the cylindrical wall 10 of the box, as clearly shown. This cover may be entirely removable from the box, but is 75 preferably hingedly connected thereto by means of a tongue 15 which extends from the rear portion of the flange 14 at its lower edge and which engages about a pintle bar 16 formed by bending outwardly a portion 80 of the body of the box defined between horizontally extending spaced slits 17 formed in the wall 10 of the box. This top or hinge construction permits the box and its cover to be each stamped from metal by suitable 85 dies and to be assembled without the use of solder, rivets or other fastening means of like nature.

As a rule, the peripheral flange 14, intermediate its height, is formed with an in- 90 struck annular bead 18 which forms a stop shoulder for limiting the downward movement of the cover when the latter is closed and also as a support for a split resilient locking ring 19 by means of which a mirror 20 may be secured against the inner face of the top 13 of the cover. As shown in Fig. 2, the mirror is slightly less in diameter than the diametric distance between opposite sides of the bead or shoulder 18 in order that it may be positioned against the top 13 and the locking ring is of such size that when it engages beneath the bead it will project slightly over the edge of the mirror and secure it in place. One end of the locking 95 ring is outbent, as shown at 21, to facilitate its application or removal and the portion of the locking ring adjacent said outbent end bears against the other end of the ring to more firmly anchor it in place by holding it 100 in expanded position.

The rouge, as indicated at 22, is pressed

against the inner face of the bottom 12 of the box and forced into the enlarged lower end of the box formed by flaring the lower portion of the wall 10 in such a manner that 5 the entire cake or tablet of rouge is firmly anchored in the bottom of the box without the employment of adhesives or other securing means. Preferably, the cake or tablet of rouge thus provided is formed with a concave upper face in order that it may be more accessible and a puff 23 is provided of suitable size to fit snugly within the box between the rouge and mirror 20.

In Figs. 4 and 5 of the drawings, I have 15 illustrated a vanity box which is identical in construction with that shown in Figs. 1 and 2, with the exception that instead of locking a mirror against the inner face of the cover of the box, the bottom 12' of the box is somewhat thickened and has its outer face recessed to receive the mirror 20' which is secured in place by a spring locking ring 19' corresponding to the locking ring 19 and engaging beneath an undercut shoulder 24 20 formed about the recess in the bottom of the box. Obviously, with this form of vanity box, a second mirror may be secured within the cover, if desired.

As will be seen from the foregoing description, when taken in connection with the drawings, I have provided an ornamental form of rouge box which firmly holds the rouge in place in such a manner that it is readily accessible although in such a manner 30 that it will not break in transit. The entire box, with its rouge cake and puff, is very compact and may be readily carried in a purse.

Although I have described the box as being formed of metal, it will, of course, be understood that it may be made of glass, pressed paper, celluloid, hard rubber or any

other suitable material, if desired. I therefore reserve the right to make any changes, within the scope of the appended claims, 45 without in the slightest degree departing from the spirit of my invention.

Having thus described the invention, what is claimed as new is:

1. A vanity box including a box proper, 50 a cover having an encircling flange hinged to the box in such a manner that the flange encircles the upper edge of the box when the cover is closed, the flange of said cover being formed with an instruck annular bead 55 intermediate its height forming a stop to limit the closing of the cover, a removable element located against the inner face of the cover, and a split resilient locking ring engaging between the peripheral edge of the 60 element and the bead to lock the element in place.

2. A vanity box including a body having a closed bottom formed with a recess in its outer face having an undercut shoulder, a 65 removable element seated in the recess, and a spring locking ring engaging the element and beneath the shoulder to lock the element in place.

3. A vanity box including a box body having a bottom and a peripheral wall, the lower portion of the peripheral wall being upwardly and inwardly inclined and the remaining greater portion of the wall being vertical whereby rouge positioned in the box 70 and pressed against the bottom will have a portion of it forced beneath the upwardly and inwardly inclined portion of the peripheral wall of the box to anchor the cake formed by the pressure exerted in the box 75 and to provide a puff receiving space above the cake, and a cover for the box body.

In testimony whereof I affix my signature.

WILLIAM G. KENDALL. [L. s.]
